STATOR MOUNTING FOR VARIABLE CONDENSERS

John H. Teaf, Moorestown, N. J., assignor, by mesne assignments, to Condenser Development Corporation, Newark, N. J., a corporation of New Jersey

Application October 6, 1938, Serial No. 233,591

5 Claims. (Cl. 175—41.5)

This invention relates to means for insulatingly mounting an electrical apparatus in a frame or support member and, specifically, I have shown my invention as applied to the mounting of the stator unit of a variable condenser in a frame carrying the rotor and stator units.

Heretofore it has been proposed, in some cases, to mount the insulators carrying a condenser stator in a frame by providing openings in the frame and inserting the ends of the insulators therein and then forcing the metal of the frame against the sides of the insulator. Since condenser frames are now usually made of steel, which has a high elastic limit, there is a tendency for the metal to spring back a certain amount away from the insulator, thereby leaving it loose in its opening. Another form of fastening such insulators to the frame has consisted of staking metal tines over the insulators, but since the staked portions of the metal engage a relatively small area on the insulator, any extra blow or force applied to overcome the spring-back effect is apt to crush or crack the insulator.

After considerable study and many tests, I have found a way of overcoming this difficulty or trouble, and this is the principal object of my invention; that is to say, the provision of ways and means for attaching the insulator directly to a frame or support member without the use of screws, rivets and the like, and without injuring the insulator, and providing a secure attachment between the insulator and the frame or support member.

I have found that in prior art staking methods the stroke of the press or ram is critical, as too little pressure results in loose parts and too much pressure invariably shatters or cracks the insulator. My invention overcomes these objections and at the same time the tools used are very much simpler than those required in the said prior art staking operations. Furthermore, with my method of assembly, the life of the tools is greatly lengthened. Hence, the whole assembly is simpler, cheaper and more effective than those to which reference has been made.

My invention will be best understood by reference to the annexed drawing, wherein:

Figure 1 shows a two-gang condenser, the rotor and stator units being shown merely in outline.

Figure 2 is a bottom view of Figure 1.

Figures 3 and 4 are end and side views of one form of a slug device which is used in the process.

Figure 5 shows the apparatus for and illustrates certain steps to be taken in the assembly

operation of the insulator to the frame or support.

In the different views, 1 is the base portion of a frame having upturned ends 2 and 3 which support a rotor shaft 4 carrying the required number of rotor units, two, 5 and 6, being illustrated, the stators being illustrated by the numerals 7 and 8. The base 1 is provided with a plurality of openings to receive the ends of insulating strips which support the stators. For example, the stator 7 is supported by insulating strips 9 and 10 while the stator 8 is supported by the insulating strips 11 and 12.

A description of the mounting of one stator will apply to both or any number of stators which might be mounted in a frame to accommodate them. The base portion 1 of the frame is provided with openings materially wider than the thickness of the insulators 9 and 10. To assemble the insulators 9 and 10 to the frame, the frame is placed in a die 13 with the base portion 1 resting on the top of the die. The die has recesses to receive the ends of the insulators 9 and 10 to the opposite ends of which have first been attached terminal strips 14 and 15 by means of bent-over lugs 22 which rest in notches in the sides of the insulators, and have their ends bent over the back side of the insulators.

With the insulators 9 and 10, having their terminals 14 and 15 attached thereto, inserted in place in the die 13, the frame is placed on the die 13 in inverted position as shown in Figure 5. Then the slugs 16, shown in Figures 3 and 4, are placed in the space between the side of the insulators and the wall of the openings in the frame 1, the diameter or width of the slugs 16 being such that they may be readily put into place. Then a punch 17, having projections 18 and 19 positioned to engage the slugs 16, is brought down onto the slugs which are of malleable or deformable metal such as aluminum, soft zinc, etc., having a relatively low elastic limit, and the slugs which rest against the top of the die 13 are squeezed by the punch members so that the metal of the slug is expanded to fill substantially the entire space between the insulators 9 and 10 and the wall of the opening in the frame 1, it being understood that the slugs are large enough in diameter to provide the necessary metal for filling this said opening so as to make a smooth and workmanlike looking job after the squeezing operation has taken place. By this method of assembly, the slug is caused to engage the insulator over its entire length in the opening and over the full thickness of the wall of the frame, and squeezes the insulator tightly into fixed position without any

danger of shattering or cracking it, thereby making a more secure fastening than any other method of which I am aware.

After the insulators have been fastened to the frame in the manner indicated, the separate stator unit or units may then be placed in the frame and their tie bars 20 are then attached to the finger portions 21 of the terminal strips 14 and 15 of the respective insulators. The method of attachment is that of soldering such as disclosed in Cramer Patent 2,087,902, issued July 27, 1937.

From what has been said it will be seen that the stator unit per se merely comprises its plates attached to its tie bars 20 in spaced relation, while the insulators with their terminal plates attached are fastened to the frame, forming a separate unit therewith.

While I have shown only one type of slug member in Figures 3 and 4, the exact shape of the slug may be varied over a considerable range without departing from the spirit of my invention or the scope of the appended claims.

What I claim is:

1. A stator mounting for a variable condenser including a frame having openings, a group of plates held together by tiebars forming a complete stator, insulating strips having one end thereof located in said openings, deformable metal slugs wedged in said openings between an insulator end and a wall of the opening in which it is located, forcing the insulator end against an opposite wall of the opening, the slug, after being wedged into place, substantially filling the remainder of the opening not occupied by the insulator, the insulator extending away from the frame and having a terminal plate at its free end, and means on the plate extending adjacent a stator tiebar for attachment thereto after the stator is positioned in the frame.

2. A stator mounting for a variable condenser

including a frame having a base with openings therein, a group of plates held together by tiebars forming a complete stator, insulating members having ends located in said base openings and deformable metallic slugs forced into said openings against the ends of said insulating members and the wall of the opening to securely anchor them in said base openings, the free ends of said insulating members extending toward the stator tiebars and having means for completing an attachment to said bars.

3. In a variable condenser having a rotor, a stator and a frame; means for mounting the stator in the frame including a pair of oppositely disposed insulators initially fastened to the frame, the fastening comprising openings in the frame to receive the ends of said insulator and deformable metallic strips forced into the openings against the wall thereof and the insulator end therein, the free end of the insulators having means extending toward the stator for completing an attachment thereto.

4. In an electrical apparatus having a frame for carrying parts of the apparatus, an insulating support, for certain of said parts, fastened to the frame, said fastening including an opening in the frame to receive the insulating support, and a deformable metallic slug forced into the opening against the wall thereof and the insulating support which extends from the frame.

5. In a variable condenser having fixed and movable electrodes, the combination of a metallic frame having openings therein and insulating pieces for supporting the fixed electrodes of the condenser, portions of said insulating pieces extending into said openings, and malleable slugs positioned in and distorted in said openings against said portions of said insulating pieces for fastening them securely in said openings.
